UNITED STATES PATENT OFFICE.

JOHANN URBANEK, OF VIENNA, AUSTRIA-HUNGARY.

GLAZIER'S DIAMOND.

SPECIFICATION forming part of Letters Patent No. 408,055, dated July 30, 1889.

Application filed June 1, 1888. Serial No. 275,709. (No model.)

To all whom it may concern:

Be it known that I, JOHANN URBANEK, a subject of the Emperor of Austria, and a resident of Vienna, in the Empire of Austria, 5 have invented certain new and useful Improvements in Glaziers' Diamonds, of which the following is a specification.

In the glaziers' diamonds heretofore used the mounting for holding the diamond or cutter is either firmly connected with the handle or forms a parallelopiped, which is made somewhat sloping below and is fitted to turn a little upon the prolongation of the handle. Both 10 kinds of tools have the disadvantage that they cannot be safely guided or effect a perfectly- 15 rectilinear cut without the employment of a rule. The former disadvantage is especially great if the cutting must be performed by guiding the tool with the unaided hand—for 20 example, in the case of curves—and good results can be obtained only after long practice. To obviate these defects is the object of the present invention, which is illustrated in the accompanying drawings.

25 In Figure 1 the improved glazier's diamond is shown in its normal position, and in Fig. 2 in the position it occupies in the cutting operation.

This tool comprises a block *a*, in which the 30 diamond or cutter *b* is set, and a handle *c*, to which the said block is jointed, so as to be capable of turning a little upon a pivot or axis *d*, arranged at a right angle to the longitudi-

nal axis of the handle. The block *a* is for this purpose provided with a cavity *f*, in which the 35 end of the handle *c* is located, the latter being connected with the block through the medium of the aforesaid pivot or axis *d*. A second obtuse diamond *g*, which is arranged in proximity to the rear end of the block in such 40 a manner that it can be adjusted parallel or approximately parallel with the longitudinal axis of the handle by a small screw *h* or other adjusting device, is adapted to guide the diamond or cutter placed somewhat eccentrically 45 to the axis *d*.

Provision can be made on the handle—such as, for example, at *l*—for breaking the glass after making the cut.

Having now particularly described and ascertained the nature of my said invention and in what manner the same is to be performed, I declare that what I claim is—

A glazier's diamond consisting of a recessed head or block, a handle pivoted within said recess, and two diamonds or cutting-points, one of which is stationary and eccentrically disposed with reference to the pivot of the handle, while the other is adjustably secured to the block, substantially as described. 55 60

In testimony whereof I have affixed my signature in presence of two witnesses.

JOH. URBANEK.
